United States Patent

[19]

Antone

[11] Des. 243,242

[45]  Feb. 1, 1977

[54] WOOD BURNING STOVE

[76] Inventor: Lawrence J. Antone, Star Route,
Dalton, Mass. 01226

[] Term: 14 Years

[21] Appl. No.: 547,567

[22] Filed: Feb. 6, 1975

[51] Int. Cl. .... D23—03

[52] U.S. Cl. D23/93

[58] Field of Search D23/72, 77, 93, 94,
D23/119, 120, 97; D7/111, 112, 117, 126;
126/58, 59, 60, 120, 121

[56] References Cited

U.S. PATENT DOCUMENTS

842,995 2/1907 Barker 126/58

969,605	9/1910	Cudd	126/58
3,292,609	12/1966	Powell	126/59
D. 214,604	7/1969	Schrock	D7/112

Primary Examiner—Wallace R. Burke

Assistant Examiner—B. J. Bullock

Attorney, Agent, or Firm—Leonard Weiss

[57] CLAIM

The ornamental design for a wood burning stove, as shown and described.

DESCRIPTION

The sole FIGURE is a perspective view of a wood burning stove showing my new design, the rear and side opposite that shown are flat and unornamented.

U.S. Patent

Feb. 1, 1977

Des. 243,242